UNITED STATES PATENT OFFICE.

BERNARD DIBNER, OF BROOKLYN, NEW YORK.

ELECTRICAL T CONNECTER.

Application filed March 31, 1924. Serial No. 703,143.

My invention relates generally to electrical connecting apparatus and has reference specifically to a type of connector known commercially as a **T** connector and used for connecting cables, wires, or metal tubing on electric structures. Being in particular employed outdoors in the entire range of climate, temperature, and altitude, it is subject to such stresses as are produced by violence of wind and storm, the strains of snow and sleet and their vibrations and also the inherent vibrations of alternating current apparatus including stresses due to switching and surges. Seasonal and daily changes of temperature will also act thereon.

T connectors of the common type generally employed for this purpose comprise an upright stem, having a bolt to engage a conductor inserted in the bore of the stem, or engaged by the other common methods of soldering or shrink fitting, and an integral half cross-head section disposed at the end opposite the conductor. This half section is placed against a main conductor and a cap superimposed over the latter. The cap is adjusted to clamp the conductor by means of ordinary bolts which operate to clamp the integral half section and the cap against opposite sides of the main conductor. According to this construction, it will be readily apparent that the efficiency of the **T** connector depends entirely upon the two clamp bolts. If one or the other of these means becomes loosened, due to the vibrations mentioned above, an effective electrical contact is broken or dangerously impaired, causing drop of voltage, loss of energy, and a heating making all soldering and shrink-fitting connections ineffectual, and what is more serious, if the bolts work loose to a point where the cap falls away from the integral half section, the latter, no longer able to cling to the main conductor, allows the branch conductor or cable to free itself and all connection between the two conductors is broken. If the wires or other electrical conductors remained without motion, the dangers just referred to would be negligible, but in all installations where substantial lengths of conductors are used the wind and the other vibratory conditions give the conductors such motion. Vibrations of this kind soon tend to work the bolts loose, crystallize the conductors, and break soldered and fit connections.

With the above conditions in mind, it is

the purpose of the present invention to provide a **T** connector which will firmly grip the conductor tubing, etc. of such equipment, so as to avoid possible disconnection due to loosening of parts, relieve all bolts of strain, and which cannot fail to maintain constant and full electrical contact with the conductors under all conditions. I accomplish this purpose by means of a **T** connector designed and constructed according to the present invention.

The invention is illustratively exemplified in the accompanying drawings, in which Figure 1 is an elevational view of my improved **T** connector showing a main and branch conductor; and Figure 2 is a perspective view of the connector showing the parts separated.

Referring to the drawings, 10 denotes the body portion of the **T** connector and 11 the clamp plate adjustably attached to the body 10. The body 10 comprises a depending stem portion 12 having a flat inner face 13 and reinforced outer face 14, which is provided with a rib 15 projecting throughout the length of the body. Adjacent the lower end of the stem 12 and disposed on the inner face 13 are two transversely arranged parallel ribs 16 abutting the surface of a vertical conductor 17 which is engaged by a **U** bolt 18 adjustable in openings in the stem on opposite sides of the rib 15. The free ends of the bolt 18 are provided with threads over which suitable nuts 19 are adjusted against the outer face 14 to draw the closed end of the bolt 18 against the conductor 17. The upper end of the body portion 10 is provided with a hook portion 20 having a circular inner periphery beginning at the lowermost tangent point and following the curve for approximately 225 degrees of the circle. This point is then about 45 degrees past the uppermost tangent point. The end of this hook portion 20 is provided with a radially disposed flange 21 which projects longitudinally of the device to about one half the width of the **T** or the center or edge of the rib 15, which follows the curve of the hook. A second flange 22, integral with the body 10, begins at a point 90 degrees back, or to the right of the first flange 21 and completes the full width of the **T**. Each flange 21 and 22 is provided with a bolt opening 23 having its axis parallel with the plane of the other flange. According to this construction, it will be seen that the

body portion 10 has an extension on both sides of the vertical center point of about 45 degrees, which will enable the connector, if necessary, to hang onto the main conductor 24 without further clamping means, gravity acting as the securing agent.

The clamping section or plate 11 joins the body portion 10 to form a complete bore 25 for the conductor 24. This section 11 comprises a hook portion 26 having an inner periphery of 225 degrees on one-half and a flange 27 radially arranged to abut the flange 22. Likewise, the other shorter half 28 of the hook 26 is substantially 90 degrees back of the first flange 27 and is provided with a radial flange 29 adapted to abut the flange 21 of the body portion 10. The flanges 27 and 29 are provided with bolt openings 30 adapted to register with the bolt openings 23 of the flanges 21 and 22, the openings being adapted to receive suitable bolts 31 having nuts 32 adjustable against the clamping plate 11. The plate 11 is further secured to the body portion 10 by means of bolts 33 arranged in registered openings 34 in the stem 12 and straight shank 35 of the cap 11. The lower end of the shank 35 is provided with a cylindrical projection 36 having an axial bore 37 in its lower portion. The purpose of the projection 36 is to provide means to receive the end of the electrical conductor, i. e., if the conductor be a cable or wire, the latter is adapted to be inserted into the bore 37 before the U bolt 18 is clamped down, but on the other hand, if the conductor comprises a tubular member then the member is placed over the cylindrical projection 36, as shown in Figure 2 in dotted lines, portion 36 thus provides means for securing a permanent electrical connection by the methods of soldering for cable and shrink fitting for tubular conductors.

The installation of a T connector according to the present invention may be carried out as follows. Assuming that the horizontally arranged main conductors 24 are hung in the transmission busses of an outdoor equipment and that the vertical branch conductors, for example, are of copper tubing, said tubing is fitted onto cap portion 11 on the ground. At this point it is important to note a characteristically novel feature of the invention. Because of the hook character of the parts of the T connector, the branch which has been fitted in place onto cap portion 11 may from the ground be hung into position on the main conductor and all that remains to be done in the air is the bolting into position of the body member 12. In fact, it will be noted that the workman need carry nothing with him into the air but body portion 12, a wrench, and the bolts.

The U bolt grip on the vertical branch conductor prevents possible failure due to melting solder or loosening of a shrink-fit at the

area where contact between the branch and the T is made. The length of body 10 acts as a steadyng lever increasing the point of flexure of the tubing due to vibrations of wind and electro-mechanical vibrations and thus eliminates contact failures due to metallic crystallization. Mechanical and consequent electrical failure in the shank 36 at the joint is also thus prevented.

Since devices of this character are used in overhead installations, such as, outdoor and indoor substations and transmission lines, and therefore requiring means for scaling the distances, the present invention permits substantially all preparations, i. e., soldering and fitting to be made while the parts are on the ground, after which operation the T's and branch conductors may be hung on the main conductors 24 and then the bolts tightened.

It will be noted that electric conduction in the present arrangement is through the cap 11 of the connector and not through a series of auxiliary bolts as in the constructions so often used for this type of work.

What I claim and desire to secure by Letters Patent is:

1. In an electrical T connector, the combination of a body member having a contacting surface projecting beyond the vertical center line of the body to support the latter in hanging position, and a complementary cap member having a contacting surface projecting beyond its vertical center line to support the cap in hanging position, said projecting contacting surfaces cooperating to form a circumferential contacting surface.

2. An electric T connector for main and branch conductors, comprising a body member having a contacting surface adapted to embrace the main conductor and to support the body member in a free hanging position, said contacting surface terminating in radially disposed offset flanges arranged on opposite sides of a vertical center line through the main conductor, and a cap member for the body member and having a complementary contacting surface and radial flanges adapted to co-operate with the contacting surface and flanges of the body member to embrace the said main conductor.

3. A T connector, as claimed in claim 2, in which said cap member is provided with a projection to receive a branch conductor connection.

4. A T connector, as claimed in claim 2, in which said cap member is provided with a projection to receive a branch conductor connection, including means adjustable in said body member to embrace the branch conductor projecting from said cap.

5. A T connector, as claimed in claim 2, in which the cap member is provided with a projection to receive a branch conductor con-

nection, a shank for said body member having engaging ribs adapted to contact with the surface of the branch conductor, and clamping means carried by said shank and embracing the branch conductor for holding the latter into close contact with said ribs.

6. In a **T** connector, the combination of a clamping member having off-set radially arranged clamping flanges, and a complementary clamping member having offset radially arranged clamping flanges, said clamping members being provided with connecting surfaces adapted to embrace an electrical conductor by adjustment of the corresponding clamping flanges of both members towards one another and a depending stem for one of said clamping members.

7. A **T** connector, as claimed in claim 6, including means carried by the first clamping member to embrace a conductor disposed at right angles to the first conductor.

8. A **T** connector, as claimed in claim 6, including an adjustable **U** bolt to engage a second conductor at right angles to the first conductor.

9. A **T** connector, as claimed in claim 6, including an adjustable **U** bolt carried by the first clamping member to engage a second conductor at right angles to the first, and a connecting member carried by the

complementary clamping member to receive the end of the second conductor above the said **U** bolt.

10. A **T** connector for connecting vertical conductors to horizontal conductors, comprising a body portion having a cross-head portion provided with radially arranged clamping flanges off-set from one another on opposite sides of a vertical center line through the horizontal conductor, said flanges being further off-set from one another on opposite sides of an intersecting point of the same center line and a vertical plane line disposed transversely through the body portion, a complementary portion having off-set flanges to receive the first flanges, means for clamping the flanges together, and means carried by the body portion to clamp the vertical conductor. 50

11. In a **T** connector, the combination of a cap member, a body member, and bolts for clamping said members about an electric conductor, said bolts being positioned so that the respective planes which are parallel 55 to said conductor and pass through said bolts will form a plurality of angles with respect to each other.

In testimony whereof, he has signed his name to this specification this 24th day of 60 March, 1924.

BERNARD DIBNER.
